COMBINED SHIPPING AND DISPLAY PACKAGE

James J. Jackson, Woodbury, N. J., assignor to
 Sandura Company, Inc., Paulsboro, N. J., a
 corporation of New Jersey

Application October 30, 1933, Serial No. 695,902

4 Claims. (Cl. 206—44)

This invention relates to a display package for decorative sheet goods.

Heretofore it has been customary in the merchandising of rolled decorative sheet goods such as floor coverings to stand the roll on its end, the exterior winding of the roll displaying the pattern of the decoration. Thus the edge of that end of the rolled sheet goods that is in contact with the floor has been subjected to the entire weight of the roll and as a result to a certain extent bent out of shape, and sometimes damaged by impacts incurred in moving. Also the outer winding of the roll and upper end are frequently open to dust and dirt and soon have the appearance of being shopworn.

One object of this invention is to provide in a display package for rolled decorative goods, a sturdy container having a combined transparent protecting film and window extending around the roll of goods to afford convenient display and inspection.

Another object is to provide a combination protective and display package capable of protecting the goods against dirt and breakage while yet insuring ease of inspection.

The above and other features are described and claimed in the following specification and claims and illustrated in the accompanying drawing, in which:

30 Figure 1 is a perspective view of a roll of decorative sheet goods illustrating the relative position of the transparency inserted therein;

Figure 2 is a view showing the transparency encircling the roll, and one of the tubes in a final position;

Figure 3 shows the transparency bound in position relative to the roll;

Figure 4 shows the package in closed form for shipment; and

40 Figure 5 shows an enlarged view, partly broken away, of the complete display package enclosing a roll of decorative covering for either display purpose or inspection.

Referring to the several figures of the drawing in detail, like reference characters identify like parts throughout the several views.

The invention involves the use of two stout tubes 1 and 1^a of card board or paper fiber, each having one end open and one closed, a transparent sheet 2 called for convenience a "transparency", and a roll of goods 3 with which latter the tubes and transparency cooperate to complete the display package.

The sheet of transparency 2 is introduced in 55 between the body of the roll 3 and the extreme

end portion or last lap 3^a thereof, as shown in Figure 1. In Figure 2 the transparency 2 is shown as completely encircling the roll 3 with both roll and transparency tightly rolled. The tube section 1, designated as the "bottom" section of pair of tubes 1 and 1^a, has been slidably fitted over one end of the roll until the end of the roll engages the inner end of the tube section. In this position it covers the adjacent edge 2^b of the transparency. The roll is then allowed to expand to the inside diameter of the tube 1, thus securing between the tube and the adjacent body of the roll the edge portion 2^b of the transparency.

In order to prevent the transparency from slipping out of position, lengthwise of the roll, the former is secured to the roll by tape, preferably transparent tape, placed in position along its circumferential edge exteriorly of first mentioned "bottom" section, as at 4, Figure 3. The transparency is also bound down by similar means, part or all of the way along its longitudinal edge exteriorly of the first tube 1, as shown at 5 in Figure 3.

The second section or tube 1^a, designated as the "top" section, is then slidably fitted over the other end of the roll 3 opposite from that covered by the first or bottom tube 1, to a position over the adjacent end 2^a of the transparency 2. Inspection position of the upper tube section is illustrated in Figure 5 in an enlarged view which shows a checked pattern on the decorative roll 3 as seen through the transparency 2. In this view the longitudinal edge of the transparency or taped portion and also the longitudinal edge 3^a of the roll is not illustrated, being on the opposite side from that viewed.

As shown in Figure 4, for shipping purposes the "top" section 1^a is slid to such a position that its inner end abuts that of the said first tube. The first or "bottom" tube 1 is already in its final position and is not moved relative to the roll until the roll is unwrapped by the consumer. In completing the package for shipping purposes, the joint made by the inner ends of the tubes 1 and 1^a abutting, may be sealed against opening by endwise movement of the tube sections.

What I claim is:

1. A display package for affording inspection of rolls of decorative sheet goods, comprising a roll of decorative sheeting, a transparency inserted between the body of said roll and the extreme end portion and encircling said roll, a pair of tubes the opposite ends being closed and the adjacent ends open, one end of said roll engag-

ing the inner end of one of said tubes and the wall of said tube tightly embracing that portion of said roll and the adjacent edge of said transparency, and the other of said tubes being slidably fitted over the opposite end of said roll and over the edge of said transparency adjacent thereto.

2. A display package for affording inspection of rolls of decorative sheet goods, comprising a roll of decorative sheeting, a transparency in contact with and encircling said roll, a pair of tubes the opposite ends being closed and the adjacent ends open, one end of said roll engaging the inner end of one of said tubes and the wall of said tube tightly embracing that portion of said roll and the adjacent edge of said transparency, and the other of said tubes being slidably fitted over the opposite end of said roll and over the edge of said transparency adjacent thereto.

3. A display package for affording inspection of rolls of decorative sheet goods, comprising a roll of decorative sheeting, a transparency inserted between the body of said roll and the extreme end portion and encircling said roll, a pair of tubes the opposite ends being closed and the adjacent ends open, one end of said roll engag-

ing the inner end of one of said tubes and the wall of said tube tightly embracing that portion of said roll and the adjacent edge of said transparency, and the other of said tubes being slidably fitted over the opposite end of said roll and over the edge of said transparency adjacent thereto, said transparency being secured to said roll along its circumferential edge beneath said second tube and bound down along its longitudinal edge exteriorly of said first mentioned tube.

4. A display package for affording inspection of rolls of decorative sheet goods, comprising a roll of decorative sheeting, a transparency encircling said roll, a pair of tubes the opposite ends being closed and the adjacent ends open one end of said roll engaging the inner end of one of said tubes and the wall of said tube tightly embracing that portion of said roll and the adjacent edge of said transparency, and the other of said tubes being slidably fitted over the opposite end of said roll and over the edge of said transparency adjacent thereto, said transparency being secured to said roll along its circumferential edge beneath said second tube and bound down along its longitudinal edge exteriorly of said first mentioned tube.

JAMES J. JACKSON.
